UNITED STATES PATENT OFFICE.

PAUL KARDAETZ, OF BERLIN-REINICKENDORF, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

CLOSED-CIRCUIT RELAY.

1,426,993.

Specification of Letters Patent. Patented Aug. 22, 1922.

Application filed December 13, 1921. Serial No. 522,116.

To all whom it may concern:

Be it known that I, PAUL KARDAETZ, a citizen of the German Empire, residing at Berlin-Reinickendorf, Germany, have invented certain new and useful Improvements in Closed-Circuit Relays, for which I have filed applications for patent in the following countries: Germany, December 11th, 1920, Serial No. S. 54,994; France, November 1st, 1921, Serial No. 151,366; England, November 1st, 1921, Serial No. 29,010/21; Belgium, November 2nd, 1921, Serial No. 239,567, and of which the following is a specification.

In working with relays operating on a closed circuit, wherein the armature is intended to drop into "off" position when the circuit is once opened, the disadvantage exists that in the case of very short interruptions of the closed circuit current flowing through the winding of the relay, the armature does not drop. This occurs because in the case of a sudden interruption of the current, the magnetic lines of force issuing from the poles of the relay and passing into the armature, do not disappear instantly but only after the expiration of a certain period of time, however short it may be. When therefore, in the case of a sudden interruption of the current, the armature is caused by the action of its own weight or of a spring, to move a slight distance away from its poles, it still remains within a magnetic field of considerable strength by which the armature is still attracted to a certain degree. Thus, if a new closure of the circuit should occur before the former field has entirely disappeared, the armature will be attracted anew. The short interruption of the current results, therefore, only in producing a temporary detachment of the armature but not in a complete drop of the latter.

Attempts have already been made to remove those disadvantages by making the magnetic pull upon the armature very slight so that only a slight weakening of the magnetic field is required in order to cause the armature to drop.

This arrangement has, however, the disadvantage of rendering the relay very sensitive to vibration, that is to say, slight mechanical forces acting upon the relay have the effect of causing the armature to

drop without the current having been interrupted.

The present invention has for its object to provide an improved closed circuit relay wherein the above disadvantages are obviated, and wherein a certain drop of the armature will take place even in the case of interruptions of the current of extremely short duration.

This object is attained by changing the path of the magnetic lines of force entering or passing through the armature at the very beginning of the dropping movement of the armature in such manner that, although there still remains a path through the armature available for these lines of force, they will not be able, in taking this path, to exert any longer any pull upon the armature, tending to restore it to its original "on" position.

The effect of this arrangement may be further increased by changing the path for the lines of force through the armature initiated by the interruption of the current, to such an extent that a torque or pull on the armature in the opposite direction is generated whereby the armature is completely moved into and maintained in its "off" position.

The accompanying drawings illustrate constructional examples of this invention.

Figures 1 and 2 illustrate in two different working positions an arrangement wherein the dropping armature is kept by spring force alone in its dropped position; and

Figures 3 to 5 illustrate an arrangement in three different working positions, wherein the spring force is assisted by the re-created field in dropping the armature into the "off" position.

Referring to Figures 1 and 2, 1 is the iron core of the relay. 2 is the armature pivotally mounted on the axle-pin 3. This armature is of elongated form and of such shape that its surfaces 4 and 5 present a large entrance surface to the lines of force issuing from the correspondingly shaped poles of the electromagnet. 6 is a spring acting upon the armature so as to give it a tendency to drop into "off" position. 7 is a contact spring fixed to the armature; it may serve in the circuits in which the relay is used, for instance to close the contacts

8 or 9 according to the position of the armature.

Figure 1 shows the armature in the "on" position. When the current flowing through 5 the electromagnet is interrupted, there will be formed, immediately on the commencement of the dropping movement, an air gap between the surfaces 4 and 5 and the magnet poles. The result of this is that owing 10 to the considerable resistance offered to the flux by the air gap near the ends of the armature the slowly disappearing magnetic lines of force will immediately be crowded together at the portions 10 and 11 of the 15 poles where they will encounter only a small air gap resistance, and at these points the lines will pass transversely through the armature, close to the axis of the latter, where-as the former magnetic field in the air gap 20 between the armature ends and the pole pieces will immediately cease. When the magnetic field is again created by a fresh closure of the circuit, this magnetic field will naturally be generated first between the 25 pole portions 10 and 11. But since the magnetic field generated in the armature between these pole portions traverses the armature transversely and near or at its pivotal center, it cannot cause any return movement 30 of the armature to "on" position and therefore the armature will be caused by the action of the spring 11 to completely move into the position shown in Figure 2, even after the relay is completely reenergized.

35 Figures 3 to 5 illustrate a constructional example wherein the armature 2 has such a shape that when it commences to drop from the position shown in Figure 3, the re-energization of the relay will now assist the 40 spring in moving the armature into the "off" position. The manner of operation in this case is again such, that when the relay circuit is opened, a large air gap will immediately form between the armature ends and 45 the pole faces, and the remaining lines of force will be crowded together at those points of the poles situated opposite the pivotal center of the armature. These lines of force will therefore pass through the 50 armature at a point at which they are not able to exert any torque upon it as is shown in Figure 4.

The magnetic field which is regenerated as a consequence of a re-energization of the relay, then serves in combination with the 55 action of the spring 6, to attract the armature in the opposite direction as will be clearly perceived from Figure 5, in which the armature is shown in full "off" position.

60 Instead of moving the armature into "off" position by means of a spring as shown, it is of course possible to obtain the same effect by a gravity device as an equivalent of the spring action.

65 Since comparatively large surfaces of the

armature contact with the pole pieces when the relay is energized, it is almost impossible for the armature to drop off as a result of mechanical vibration notwithstanding the sensitiveness of the relay for short interruptions of current.

For the purpose of attaining a very high degree of sensitiveness of the relay, it is possible to employ pole pieces and armatures of the relay having weak magnetic saturation so that the shifting of all the lines of force in the pole pieces to a predetermined place can be more easily effected.

I claim:—

1. A closed circuit relay having poles and 80 an armature designed to have an "on" and "off" position and being pivotally disposed midway between its ends and between said poles and permitting the flux to pass lengthwise through it when in "on" position, means 85 tending to throw said armature into "off" position and adapted to partly remove it from the "on" position when the relay is temporarily de-energized, said armature being wider at its central portion than at its 90 ends, causing the re-energization flux to pass transversely through said portion when the armature is partly removed from the "on" position, to permit said throw-off means to remove it entirely into "off" position. 95

2. A closed circuit relay having poles and 100 an armature designed to have an "on" and "off" position and being pivotally disposed midway between its ends and between said poles and permitting the flux to pass lengthwise through it when in "on" position, means tending to throw said armature into "off" position and adapted to partly remove it from the "on" position when the relay is temporarily de-energized, said armature being wider at its central portion than at its 105 ends, causing the re-energization flux to pass transversely through said portion when the armature is partly removed from the "on" position, to permit said throw-off means to remove it entirely into "off" position, said armature when approaching "off" position 110 permitting the re-energization flux to pass lengthwise through it, but in a direction reverse to that when in "on" position, to assist 115 said throw-off means to completely move the armature into and hold it in "off" position.

3. A closed circuit relay having poles and 120 a diamond shaped armature designed to have an "on" and "off" position and being pivotally disposed midway between its ends and between said poles and permitting the flux to pass lengthwise through it when in "on" position, a spring tending to throw 125 said armature into "off" position and adapted to partly remove the armature from the "on" position when the relay is temporarily de-energized, the larger central portion of said armature causing the re-energized flux to pass transversely through said central 130

portion when the diamond ends are partly removed from the "on" position to permit said spring to move the armature entirely into the "off" position.

5. 4. A closed circuit relay having poles and a diamond shaped armature designed to have an "on" and "off" position and being pivotally disposed midway between its ends and between said poles and permitting the 10 flux to pass lengthwise through it when in "on" position, a spring tending to throw said armature into "off" position and adapted to partly remove the armature from the "on" position when the relay is temporarily de-energized, the larger central

portion of said armature causing the re-energized flux to pass transversely through said central portion when the diamond ends are partly removed from the "on" position to permit said spring to move 20 the armature entirely into the "off" position, said armature when approaching the "off" position permitting the re-energized flux to pass lengthwise through it, but in a direction reverse to that when in "on" 25 position to assist said spring to completely move the armature into and hold it in "off" position.

In testimony whereof I affix my signature.

PAUL KARDAETZ.
